TEXTILE DRAWING FRAME

Roderic D. Tarr, Biddeford, Maine, assignor to
 Saco-Lowell Shops, Boston, Mass., a corporation
 of Maine

Application May 25, 1943, Serial No. 488,331

2 Claims. (Cl. 19—130)

This invention relates to drawing frames of the type commonly used in the manufacture of cotton yarn in doubling and drawing strands of roving or sliver. For example, it is a common practice to double four, six or eight strands of card sliver or roving and to draft them in a drawing frame to produce a single roving which will be more uniform in composition than were any of the constituent strands from which it was made. Often this doubling and drawing operation is repeated one or more times before the resulting roving is taken to the next step in the customary process of manufacturing cotton yarn.

These drawing frames comprise a series of pairs of intermeshing fluted rolls, positioned one in advance of another, through which the web composed of the rovings is fed, each successive pair of rolls being driven at a slightly higher peripheral speed than the preceding pair so as to produce the desired draft. The web issuing from between the delivery rolls is gathered and led into a coiler.

In order for such a machine to function properly, the fluted rolls must be manufactured with a high degree of accuracy. This necessarily increases materially the expense of manufacture of the machine. That such accuracy is necessary will be evident from the consideration that the effect of inaccuracy is cumulative as the machine operates. That is, if, due to such inaccuracies, one pair of rolls feeds at, say, one thousandth of an inch slower per revolution at one end than at the other, then at the end of one thousand revolutions the error will amount to a length of one inch. While as slight an error as this will be lost in the draft, a somewhat larger error may well result, in the course of a few hours run, in producing a sag in the web between two successive pairs of rolls, thus nullifying the drafting operation at this point. In any event, such errors tend to defeat the object of the doubling and drawing process, which is to produce a strand having greater uniformity than do the original strands.

The present invention deals especially with these considerations, and it aims to devise a drawing frame in which the desired degree of accuracy can be obtained more economically and with more certainty.

The nature of the invention will be readily understood from the following description when read in connection with the accompanying drawing, and the novel features will be particularly pointed out in the appended claims.

In the drawing,

Figure 1 is a vertical, sectional view of a head of a drawing frame with some parts shown in elevation; and

Figure 2 is an enlarged sectional view of small cooperating portions of one pair of the rolls illustrated in Fig. 1.

Referring first to Fig. 1, the construction there shown comprises four pairs of metallic intermeshing rolls including bottom rolls 2, 3, 4 and 5 and top rolls cooperating with the respective bottom rolls and indicated at 6, 7, 8 and 9. The bottom rolls are positively driven by gearing but the top rolls are driven simply through their relationship to the bottom rolls and through the intervening fiber or "grist." Weight hooks 10, 11, 12 and 13 bear on the gudgeons of the respective top rolls and are of such mass as to make each pair of rolls grip the web of fibers with sufficient pressure for operating purposes. Each successive pair of rolls, proceeding from right to left, is driven at a sufficiently higher speed than the preceding pair to produce the desired draft. The arrangement shown also includes the usual hinged top cover 18 equipped with a clearer cloth 19.

So far as the general organization of the construction just described is concerned, it may be exactly like those in common use, and it may be equipped with the usual guides, stop devices, and other accessories ordinarily used in drawing frames. A customary arrangement is to draw the strands of roving or sliver from supply cans set up at the right-hand side of the machine, to feed them together in the form of a web W through the rolls, and then to guide the reduced web issuing from the front or delivery rolls 2 and 6 into the trumpet of a coiler which deposits the drawn strand in a roving can. In some cases, also, one or more of the top rolls 6 and 7 are replaced with smooth surfaced cushioned covered rolls, and in some machines, also, the number of rolls is increased. Such changes or modifications are immaterial from the standpoint of the present invention.

According to this invention one or more of these pairs of rolls are fluted in the manner indicated in Fig. 2. That is, the bottom roll is milled, or manufactured by any other suitable fluting method, to produce ribs a of the form there shown, and these ribs are separated by intervening round-bottomed grooves b. After the fluting operations have been completed the roll is ground very accurately to a given outside diameter, the tolerance from one end to another of the roll being preferably within two-thousandths of an 55 inch. This grinding operation produces small

flattened tips *c* on the rounded ends of the ribs *a*. The top roll *9* is also milled, as shown in Fig. 2, to produce round-ended ribs *d* which are shorter in radial dimensions than the ribs *a* of the bottom roll, and these ribs *d* are separated by round-bottomed grooves *e* like the grooves *b*. The flutes in both rolls have the same pitch. In making the top roll, however, no effort is made to obtain extraordinary accuracy in either its inside or outside diameter, but the depth of flute is maintained with a high degree of accuracy. In other words, the depth of flute is constant from one end to the other, and this result may be readily produced by making the same milling cutter which shapes a rib also form the bottom of the adjoining groove simultaneously. Also, the radius of curvature of the grooves is somewhat, say four or five-thousandths, larger in the top roll than in the bottom roll. The construction shown in Fig. 2 is drawn substantially to scale and is enlarged on a twenty to one ratio.

The important feature of this arrangement is that the bottom roll has a constant outside diameter from end to end of the fiber working area thereof, while the top roll has a constant depth of flute throughout its fiber working area irrespective of minor manufacturing errors in diameter. Consequently, and because the lower roll is positively driven, and also because a substantial clearance of something in the order of ten to fourteen-thousandths of an inch is provided between the flutes of the top roll and the walls of the grooves of the bottom roll, the latter roll controls the rate of feed of the fibrous web irrespective of the diameter of the top roll. With this construction, therefore, the rolls *9* and *5* will produce a uniform delivery or rate of feed of sliver across their entire fiber engaging surfaces. And this result is produced by the presence of cooperating features of accuracy in the two rolls which are easily produced by relatively inexpensive manufacturing operations.

All, or any desired number, of the pairs of rolls in a drawing frame may be made in this manner. Accordingly, the invention makes it possible to obtain, in a more advantageous manner, those results which have only been obtained heretofore in a drawing frame by the use of manufacturing processes considerably more expensive than those required in making the rolls above described.

Having thus described my invention, what I desire to claim as new is:

1. In a textile drawing frame, comprising a series of pairs of drafting rolls, mounted one behind another, to operate successively on a web composed of parallel rovings, certain at least of said pairs of rolls consisting of driven lower metallic fluted rolls and upper metallic fluted rolls, each meshing with and resting upon its respective cooperating lower roll and being driven thereby, a construction in which the outside diameter of one at least of said lower rolls is maintained with a high degree of accuracy throughout its fiber working area notwithstanding normal manufacturing variations in the depths of its flutes, and its cooperating top roll has a constant depth of flute throughout its fiber working area regardless of minor variations in its diameter, the two rolls having the same pitch of fluting and being supported in a meshing relationship but the ribs of the top roll being of smaller radial height than those of the bottom roll and having an abnormally large clearance with the walls of the grooves of the lower roll even when the ribs of the lower roll substantially contact with the bottoms of the grooves in the top roll.

2. In a drawing frame according to preceding claim 1, a construction in which said ribs of the lower roll have rounded ends with narrow flattened tops.

RODERIC D. TARR.
